United States Patent Office

Des. 198,125
Patented May 5, 1964

198,125

VEHICLE MIRROR

Frances M. Kentes, 2236 N. 39th St., Milwaukee 8, Wis.,
assignor of two-fifths to John P. Kentes, Milwaukee, Wis.

Filed July 6, 1962, Ser. No. 70,823

Term of patent 14 years

(Cl. D14—6)

Fig. 1.

Fig. 2.

Fig. 3.

Fig. 4

Fig. 5

FIG. 1 is a perspective view of the vehicle mirror showing my new design;

FIG. 2 is a plan view of the mirror;

FIG. 3 is a side elevation of the mirror;

FIG. 4 is a bottom view of the mirror; and

FIG. 5 is a sectional view taken along line 5-5 of FIG. 4.

The side, not shown, is a mirror image of the side shown.

I claim:

The ornamental design for a vehicle mirror, substantially as shown and described.
